UNITED STATES PATENT OFFICE

HUGO H. WERMINE, OF VILLA PARK, ILLINOIS, ASSIGNOR TO BELDEN MANUFACTURING COMPANY, OF CHICAGO, ILLINOIS, A CORPORATION OF ILLINOIS

WEATHERPROOF ELECTRIC WINDING

Application filed July 16, 1928. Serial No. 293,071.

The invention relates to weather-proof electric windings and is of particular value in connection with the manufacture of electro-magnetic devices employing iron cores, for example, transformers or analogous devices.

The principal object of the invention is to provide for an electric winding of the class described a casing which, while permitting ingress and egress of the electric current, will at the same time serve as a hermetic seal for the winding, thereby protecting the latter against moisture or other deleterious agencies which might otherwise affect the efficiency or durability of the winding.

Further objects of the invention are to provide a casing which may be employed as a support or mounting for the electric unit; to provide a casing which, besides protecting the coil from climatic conditions, will at the same time protect the coil from mechanical abuse or injury due to rough handling; to provide a unitary structure which shall be of a well finished, ornamental and neat appearance while being relatively compact in size; to provide a construction which may be rapidly and economically manufactured, and to provide an improved method or process for making the described structure, and, in general, to provide an improved, efficient and economical structure and method of the character referred to.

In certain of its aspects, the invention may be considered as a modification of or improvement on the invention disclosed in my pending application Serial No. 180,356, filed April 2, 1927.

In the drawings, I have illustrated the invention as applied to a radio transformer of the audio type, and in said drawings:

Fig. 1 represents a perspective of the finished transformer within its weather-proof casing.

Fig. 2 is a perspective view of the bobbin and terminals.

Fig. 3 is a plan view of one end of the bobbin illustrated in Fig. 2, and showing how the terminals are connected to the windings.

Fig. 4 is a side elevation of the bobbin windings and laminated core after assembly.

Fig. 5 is a perspective view of one part of

the two-part shield which encloses the active elements of the structure.

Fig. 6 is a perspective view of the transformer enclosed in its shield, portions of the latter being broken away.

Fig. 7 is a sectional view of the preliminary mold, showing the first molding operation, and

Fig. 8 is a vertical section through the mold showing the final molding operation.

Referring to the drawings, it will be observed that the bobbin, which as a whole may be designated 10, comprises a barrel 11 and a pair of heads or circumferential flanges 12 and 13. The barrel is made with a square 65 or rectangular aperture to accommodate the laminations, and the heads 12 and 13 are each made with an inside step, as shown at 14, in order to provide a proper support for the mica wrapper 15 extending around the 70 low tension or primary winding 16. The width of said flange 14 is made sufficient to insure a proper lapping of the mica wrapper 15 at its ends so that the high tension winding 17 which fills the outer space of the bobbin will not have any tendency to slip down 75 into contact with the inner or low tension winding. Said high tension winding 17 on its outside surface is protected and insulated by the mica wrapping 18, which, if desired 80 may lap over and be supported by the outer surfaces of the flanges 12 and 13 of the bobbin.

In order to facilitate the bringing out of the ends of the primary and secondary windings of the coil, I prefer to rigidly secure to one end of the bobbin a set of four relatively stiff conductor pins or terminals 19. The inner ends of these conductor pins 19 are hooked as shown at 20 and embedded in 90 small oval-shaped blocks 21 which are formed as integral parts of the head 13 of the spool 10. Preferably, the entire spool, consisting of the barrel 11, heads 12 and 13, and anchor blocks 21, is formed of material such as 95 bakelite and is molded as a one-piece unitary structure.

When molding the spool with its terminals, the ends of the hooks 20 of the conductor pins 19 are left exposed, as well shown 100

in Figures 2 and 6 of the drawings, so that the wires, as, for example, 22, which lead through apertures 23 in the spool head 13, may be connected to the inner ends 20 of said terminal pins by soldering, as shown, or in any other suitable manner.

After the spool has been equipped with its low tension and high tension windings and suitably insulated, the laminations are inserted. Preferably, these laminations are of the usual mating T and U shape, as shown at 24 and 25 in Figure 4 of the drawings. Also, after the assembly of the laminations has been completed, the fiber sheet 26 is wrapped around the edges of the laminations to insulate the edges of the same from the inner wall of a metallic, preferably steel, shield which includes the winding and laminations. This shield preferably comprises a pair of like parts, one of which, 27, is illustrated in perspective in Figure 5. As shown best in Figures 5 and 6, the shield parts are provided with a pair of apertures 28 of sufficient diameter to avoid contact with the conducting pins 19 which pass through said apertures. Also, to one of the parts 27 of the metal shield, there is secured a grounding pin 29, preferably by soldering or welding to the side of the shield, as indicated at 30. The parts constructed as above described and assembled in the condition shown in Figure 6, are now in condition to be supplied with the weather-proof casing which constitutes an important feature of the invention. Such casing is made of bakelite or analogous material capable of being molded and made hard by the application of pressure and heat. Since in the molding of such material very heavy pressure is required, usually at least one thousand pounds per square inch, it is desirable, if not essential, to prevent injury to the relatively delicate coils with which transformers of the type here described are frequently wound. In the present instance, this protection of the windings against the pressure incident to the molding operation is effected in different ways. In the first place, I provide the shield composed of the mating sheet metal parts 27 which closely abut together to effect a seal at the seam line 31 of the shield as a whole; and also it will be observed that where the terminal pins 19 extend through the shelf portion 32 of the steel shield, the said shelf portion 32 rests directly in contact with and upon the upper flat surface of the block 21, so that the bakelite cannot flow into the interior of the structure through the said apertures 28, which, as previously stated, are considerably larger in diameter than the pins 29 in order to avoid short circuits.

Furthermore, where the shield parts 27 are made of relatively light gauge metal for obvious reasons, so that they might possibly collapse under the pressure of the molding

operation if subjected to heavy side pressure of the order indicated, this difficulty is avoided by applying the major part of the molding pressure in a direction parallel with the laminations, so that the laminations of the coil structure and also the spool of the coil itself serve in a measure to resist the mold pressure and prevent distortion or collapsing of the structure with resulting damage to the electrical windings.

Also, in order still further to facilitate the molding of the casing without inconvenience and without damage to the structure, I prefer to effect the molding in two operations, which will now be described.

In Fig. 7 of the drawings, I have illustrated the cavity member 33 of the mold or die which is used in the preliminary as well as in the final molding operation. In the preliminary molding operation, the portion 33 of the mold is used in connection with a temporary plunger 34 or punch which is of proper dimensions so that the opening or recess formed by said punch will permit insertion of the shielded transformer into said cavity in the position as indicated in Fig. 8.

In the first or preliminary molding operation, the cavity of the mold portion 33 is charged with the proper amount of powdered bakelite or bakelized material and the plunger 34 is brought down in the usual way with pressure and heat applied so that there is formed in the recess of the mold portion 33 a semi-cured, open topped, shell or receptacle 35, said shell or receptacle, as above stated, being of the proper internal dimensions to permit the shielded transformer to be lowered or inserted therein.

After the preforming plunger 34 has been removed and the shielded transformer substituted therefor, as indicated in Fig. 8 of the drawings, a further supply of the bakelite powder is introduced into the top of the cavity of mold portion 33 and over the upper end and the terminals of the transformer, after which the final plunger or die portion 36 is brought down into the position shown in Fig. 8 and heat and pressure applied in the usual manner. It will be observed that the upper die portion 36 of the mold is fitted with a set of bushings as shown at 37, each of said bushings having at its lower end a conical recess 38 opening into a vertically extending bore 39, the upper end of which is of somewhat greater diameter than the lower end, which lower end substantially fits one of the pins 19 or 29 and registers therewith.

The finished article resulting from the second or final molding operation is illustrated in Fig. 1 and it will be manifest that the completed job has all of the advantages resulting from the attainment of the objects of invention above set forth.

If desired, perforated washers as indicated at 40 in Fig. 8, may be fitted over the four

terminal pins 19 to prevent possible leakage of bakelite into the interior of the shield.

The term bakelite, as used in the claims, means any kind of phenolic condensation product, or the like, which is capable of being hardened by heat and pressure.

I am aware that changes may be made in the structure and method of making the same above described without departing from the spirit of my invention, the scope of which should be determined by reference to the following claims, the same being construed as broadly as possible consistent with the state of the art.

15 I claim as my invention:

1. The method of applying a weatherproof casing to an electric winding which consists in first molding an open-ended shell, then inserting the winding into said shell, and then 20 molding a cover over said open end to completely enclose said winding while consolidating said cover material with the material of the premolded shell.

2. The method of applying a bakelite casing to an electric winding which consists in first molding an open-ended shell of partially cured bakelite material, then inserting the winding into said shell, and then molding a 25 cover over said open end to completely enclose said winding while applying heat and pressure to consolidate said cover material with the material of the premolded shell.

3. The method of applying a bakelite casing to an electric winding with projecting 30 terminals which consists in first molding an open-ended shell of partially cured bakelite material, then inserting the winding into said shell, and then molding a cover over said 35 open end to completely enclose said winding while applying heat and pressure to consolidate said cover material with the material of the premolded shell and to seal the terminals projecting outwardly through the casing.

July 13, 1928.

HUGO H. WERMINE.
